UNITED STATES PATENT OFFICE.

CLARENCE E. FLORKEY, OF DAYTON, OHIO, ASSIGNOR TO THE SCHIEBLE TOY AND NOVELTY COMPANY, OF DAYTON, OHIO, A CORPORATION OF OHIO.

WHEELED TOY.

Application filed November 3, 1922. Serial No. 598,902.

To all whom it may concern:

Be it known that I, CLARENCE E. FLORKEY, a citizen of the United States, residing at Dayton, in the county of Montgomery and State of Ohio, have invented certain new and useful Improvements in Wheeled Toys, of which the following is a specification, reference being had therein to the accompanying drawing.

10 My invention relates to toys, and in particular to power toys.

It is the object of my invention to provide a toy representing an automobile which can be economically manufactured in quantities 15 out of a minimum number of pieces.

20 A further object is to provide a toy which will be rigid and strong and which will be adapted to be used as a pull toy and also adapted to be used as a power toy which ever is preferred. The source of power is immaterial, but I prefer to employ a friction drive.

25 It will be understood that in the manufacture of toys where the amount of profit per toy is small it is essential that the production be through dies in large quantities. Because of the great expense of the dies, it is necessary to reduce the number of parts 30 of any toy to the minimum. It is also essential to reduce the amount of stock used it being a matter of considerable importance to economically utilize the stock and design the several parts so that there will be the least waste.

35 It is also desirable to have the toys simulate the appearance of actual articles of commerce as nearly as possible.

40 It is the object of my invention to provide a one piece frame, hood, body members, body side walls, and bumper support upon which there can be interchangeably mounted a roadster top and body, or a sedan top, or a coupé body.

45 It is a further object to provide a rear deck seat and floor board member which can be used for both the coupé and roadster equipments.

50 It is an additional object to provide a blank so laid out that when it is finally formed the side walls of the body and frame will be parallel while the hood will have its side walls approaching one another towards

the front and its top wall descending towards the front where the radiator is located.

55 It is a further object of my invention to provide such a lay out of blanks and dies that the minimum number of forming and piercing operations will be necessary.

60 It is an additional object to provide an interchangeable wind-shield.

Another object is to provide a fender which may be readily attached and detached for shipment and which will have its ends so concealed by the wheels that they will not 65 catch against the hands of the children operating the toys or catch in their clothes.

70 It is a further object to provide a one piece reinforced radiator which simulates the radiator on an ordinary automobile.

75 It is a further object to provide a coupé and sedan body of one piece with the exception of the wind-shield which is interchangeable with either body. These bodies are so arranged that a portion of their edges become bearing points for attachment to the frame of the automobile and the several parts have their edges interlocked in such a way as to form a rigid structure which may be spot welded together or otherwise attached.

80 It is an additional object to provide a combined running board and fenders of one piece which can be formed from the same die for both right and left hand sides.

85 Referring to the drawings:

Figure 1 is a plan view partially in perspective of the toy having a roadster body;

Fig. 2 is a similar view of the toy having 90 a coupé body;

Fig. 3 is a similar view of the toy having a sedan body;

Fig. 4 is a plan view of the body blank in its initial stage;

Fig. 5 is a plan view of the body blank 95 with the doors, louvers, and edges of the frame formed;

Fig. 6 is a plan view partially in perspective showing the body blank formed to provide the double tapered hood, side frame 100 members, and the side walls of the body;

Fig. 7 is a plan view of the rear deck body blank which is used to form the rear deck seat, floor board and dash board;

- Fig. 8 is a perspective of the complete article made from the blank of Fig. 7;
- Fig. 9 is the blank for the roadster top;
- Fig. 10 is a roadster top just prior to final assembly and spot welding;
- Fig. 11 is the radiator blank;
- Fig. 12 is the completed radiator;
- Fig. 13 is the blank for the running board and fender on one side of the car.
- 10 The same blank is used for both right and left hand running board and fenders by merely reversing the side on which the major projections will be located.
- Fig. 14 illustrates the blank after the first forming operation;
- Fig. 15 represents the blank after the last forming operation;
- Fig. 16 represents the lamp blank;
- Fig. 17 represents the completed lamp;
- 20 Fig. 18 is a plan view of the bumper installed and a part sectional view of the frame member and front wheels;
- Fig. 19 is a perspective view of the bumper;
- 25 Fig. 20 is the wind-shield, dash board, and sun shade blank;
- Fig. 21 is a perspective of the blank finally formed;
- Fig. 22 is the coupé body blank;
- 30 Fig. 23 is a coupé body blank just prior to having the parts assembled;
- Fig. 24 is a rear elevation of the sedan body showing the blank forming a part of the rear panel of the body and showing one wall in position on the left hand and the right hand wall about to be put in position;
- 35 Fig. 25 is the sedan body blank;
- Fig. 26 is the sedan body blank formed just prior to bending into shape for assembly;
- 40 Fig. 27 is a perspective of the assembled coupé body looking at a rear corner;
- Fig. 28 is a perspective looking from the front corner of the assembled coupé body, showing the wind-shield member, sun shade, etc., in position;
- 45 Fig. 29 is a side elevation of a partially completed rear wall of the sedan body and gasoline tank;
- 50 Fig. 30 is a double bar bumper blank;
- Fig. 31 is a perspective of the double bar bumper.
- 55 It will be understood that the primary purpose of this invention is to provide in a few pieces a toy which may be shaped to exactly resemble an automobile. Another purpose is to use as many parts as possible stamped from blanks to fit into different styles of automobiles. It is also necessary to have the parts interchangeable as far as possible, such as the fenders, and the dies interchangeable as in the case of the dies for the fenders.
- 60 It will be realized that my invention is applicable not only to toy vehicles but to the

manufacture of commercial vehicles wherein the same economies are necessary.

Referring to Figure 1, there will be seen a roadster which has the running wheels at the forward end designated 1, mounted on the axle 2 which is supported in the apertures 3 in the body blank shown in Figs. 4, 5, and 6.

The rear wheels 4 are mounted on axles 6 which are attached to the frame in any desired way. In this instance I use a power drive such as set forth in Patent No. 793,637 to Clark, which is carried in a frame and is readily attached by riveting or spot welding to the side walls of the body.

It is a feature of my invention to provide the same power unit, running gear, fenders, hood, radiator, and body for all three types of automobiles with three types of tops or inclosed bodies which are interchangeable, thus reducing to substantially one fundamental model three types of toys to satisfy the varying demands of the trade. The automobile consists of a body portion having side frame members 7 on either side thereof, the forward ends of which are designated 8 and are used for supporting the bumper 9 in the slots 10^a cut in the forward portions 8 of the side members.

The one-piece blank shown in Figs. 4, 5, and 6 is composed of the ears 8 which later form the forward projections on the side frame members and a central hood portion 10 which is in one-piece with the side frame members. This blank is substantially rectangular and has two separate diverging arms 11 which are partially divided from 10 by the V shaped slots 12. The purpose of these slots is an important one in that it permits of the hood portion of the blank and the side wall of the body portion of the blank 11 being finally aligned so that they are on a straight line rather than at an angle to one another as shown in Fig. 4 and Fig. 5.

This blank is shaped in such a way as to form a sloping and contracting hood towards the forward end thereof.

Consequently, the blank is first provided without the V shaped slots 12. The first operation cuts these slots, the second operation forms the blank as shown in Fig. 5, and the final operations form the body as shown in Fig. 6 with the tapering hood and vertical body side walls. The body is complete to the louvers and the molding 13 on the door. The louvers are designated 14. The cut-away portions 15 and 16 receive the rear wheels and driving mechanism. Thus the body is formed at the rear portion with two vertical members forming the side walls of the roadster body, sedan, and coupé body, as well as furnishing a support for the tops of bodies mounted on the toy.

The side walls of the hood are designated

17 and the sloping top wall retains its original designation 10. It will be noted that even the ledge between the hood and the side frame member 7 is formed at an angle to the latter. This ledge is designated 18. Thus there is provided a standard body of one piece.

When it is desired to build the roadster or coupé, I select the blank shown in Fig. 7 which after being pressed to the shape shown in Fig. 8 has an arched portion 19. The blank of Fig. 7 has a tapering tail portion 20 which is provided on either side with ears 21 which are later used for attaching the forward end of the blank to the inside of the side walls 11 by spot welding and the like. The rear end of this blank in the portion 19 has a V shaped slot 22 cut on either side thereof to permit of bending over a flange 23 at the rear end thereof designated 28. This forms a finishing rear wall for the roadster and coupé body.

As will be seen in Fig. 8 the flanges 24 and 25 are provided which fit over the top edges of the side walls 11 Fig. 6 to form attaching surfaces between the several parts. The blank portion 20 is bent (as shown in Fig. 8) to form a vertical seat back 27, a seat 28, a heel board 29, a floor board 30, and a dash board 31. These several parts are bent into position successively as may be desired.

It will be noted in Figs. 1 and 2 that this rear deck member together with the seat, floor board and dash board, is used in both the roadster and coupé types.

Upon this rear deck is fastened a spare tire and wheel, designated 32, by a clip 33 which is passed through an aperture 34 Fig. 8 in 19 and clamped on the inside of 19. This provides a useful extra wheel in case one of the wheels of the toy becomes injured thus adding to the life of the toy.

Referring to the roadster top, Figs. 1, 9 and 10 it will be seen that it is made out of one piece having two portions connected together. One portion designated 35 is the top proper and its side curtains 36 and 37. To the rear of the top proper is connected the rear curtain 38. The side curtains and rear curtain have openings 39 with embossed edges 40. The side curtain portions have ears 41 which are bent at right angles to the side curtains to form a stop for locating the top on the side walls 11. The flanges or plate 42 overlap the side walls 11 and form a sufficient space for spot welding the top to the body walls. The flanges 43 are bent at right angles to the rear wall of the top so that the overlapping side curtains or side walls will have a surface upon which they can be spot welded to assemble the top.

Referring to the radiator, it is essential to have a radiator which is very strong and rigid, exactly simulating an automobile

radiator, and made in one piece. It is necessary that the radiator have sufficient flanges to permit of overlapping the end of the hood so that the ends of the hood may be rigidly positioned. Toys of this character are subjected to heavy blows at the forward end as they are driven by friction wheel devices that give the toy considerable momentum.

Accordingly, a one piece radiator is provided consisting of a central portion 44, side flanges 45 for engaging the sides of the hood and a cap portion 46 with a flange 47 for engaging the top of the hood. The front of the radiator has a series of vertical depressions 48 which give the appearance of a honeycomb to the radiator.

The fenders and running boards together with the aprons are made from straight pieces of metal having rounded ends designated 49. On one edge there are a series of fingers 50 projecting laterally and spaced from one another to form the rear apron which is the means by which the structure is attached to the body at the rear against the side walls 11. At the forward end there are similar but larger projecting fingers, the forward one of which is designated 51 and is substantially triangular in shape. The next two are nearly rectangular in shape, such as 52 and 53, while the rear finger is triangular in shape and is designated 54. Along one edge between the fingers is a rectangular projection or flange 55 which is used for aligning the running board and fenders with the body and forming a means of attachment with the side wall of the body.

This combined running board and fender fit according to the way the die is applied; when the die is applied to one side it becomes a right hand fender and when the die is applied to the other side it becomes a left hand fender. This saves an additional die and only necessitates one form of blank, greatly simplifying the construction of the die and reducing the expense. A right angle flange 56 is provided around the entire outside edge of the entire running board and fenders to give the proper strength and appearance to the structure as well as to eliminate the sharp edge which may cut the child's hand.

Upon the final operation the arches of the fenders 57 and 58 are formed.

The head lights are formed out of a single circular sheet 59 which is cupped as at 60 and has one of its edges spot welded to the top of the fender 58.

The bumper is a piece of spring metal, such as 9, having spring loops 61, a bar 62 and outwardly turned ends 63 for the insertion in the slots 8 of the forward frame members. These outwardly turned ends also project into the cup shaped portion 64 of the wheel 1 which is so formed to represent a tire on a wheel. This allows the projection

of 63 sufficiently far enough through the frame and also protects the ends of the bumper from injuring the child and also protects it from tearing its clothes.

5 It will be observed that a blow on the forward part of the bumper 9 will serve to attach the bumper more securely to the toy. By compressing the spring ends 62 between the fingers the bumper can be detached from the toy. A bumper of this character is a great advantage as it is of soft metal, has a broad surface and both protects the toy and furniture in a house where the toy is being operated.

10 15 The wind shield or sun shade, frame, dash board, ledge, etc., are all formed from a single piece of metal shown in Fig. 20. This piece of metal has an I-shaped slot 65 cut in it.

20 25 30 One edge is arch shaped as at 66 to fit over the hood of the toy. The lower metal flap 67 is bent inwardly at right angles to form a dash board ledge 68 while the upper flap as 69 is bent upwardly at an angle to form the wind shield or sun shade. The upper edge is arched as at 70 to fit the inside of the coupé or sedan top which is arched for strength and appearance.

35 40 45 As to the construction of the coupé body which can be substituted for the roadster top, it will be understood that this coupé body has a rounded top and rounded side walls. In Fig. 22 will be seen a one piece blank which forms this body which consists of the following elements:

50 55 60 65 70 75 77 80 85 90 95 100 105 110 115 120 125 130 71 is the top of the body to one end of which is attached the rear wall 72 having the opening 73.

On either side of 71 there is attached the side wall 74 having a rectangular opening for the door as at 75 and a rear side wall opening with angular corners designated 76. On the outer edge of the side wall which later becomes the lower edge there is provided a series of teeth separated from one another by V shaped openings. These V shaped openings are designated 76 and the teeth 77. The bottom of the teeth and the bottom of the openings are laid out along a straight line which is parallel with the opposite side or top edge of the side wall of the body. The outer ends of the teeth are laid out along a circular path.

It will be seen in Fig. 23 that the purpose of having this peculiar arrangement of these teeth is to provide for the curvature of the side walls 74 in the completed body and these teeth are bent at right angles along a straight line 78 so that the base of the teeth in the completed body will be laid out along a curved line 79 and the ends of the teeth will be on a straight line as at 80. This reverses the layout of the teeth on the blank. The purpose of this is to accommodate to the side wall of the body the

wall carrying downwardly projecting portions 81 of the teeth on a line that is straight so as to make contact with the straight side of the inside of the walls 11 to which these portions 81 are spot welded.

90 95 100 105 110 115 120 125 130 In Fig. 23 there will be seen the completed blank prior to assembly into the completed coupé body. In this form the teeth 81 are so positioned that they will be vertical when the body is assembled, the side walls 74 will be semicircular, the windows will have flanges 82 and the outline of the door will be embossed as at 83. The top flanges 84 will be formed so that they will overlap the top edges of the side walls 74 to form a connection for welding the parts together. The rear wall at the top will have flanges 85 for overlapping the rear edges of the side walls. The forward edges of the side walls will have the flanges 86 to which the structure shown in Fig. 21 may be attached.

Turning to the sedan body which is quite similar to the coupé body, the blank for such a body will be seen in Fig. 25. It consists of the top 87 which has on either side thereof the side walls 88 and 89. These side walls are pierced by a series of windows 90. The side walls are disposed at an angle to the top and are so arranged that the forward end of the top is narrower than at the rear end. The top and side walls are severed from one another by the slit 91 and by the V shaped slot 92. The side walls themselves are cutaway as at 93 to permit of the rear fenders being set in beneath the side walls as the body is wider than the space between the body members 11 to which the rear members are attached. The line of bending between the top and rear wall of the body is marked by V shaped cutaway portions 94 which are provided so that when the flanges on the top as at 95 and the flanges on the back as at 96 are struck up and the top and back are at right angles to each other this bending of the parts at right angles may be accomplished. The back is designated 97 and has a rear window 98. At the bottom of the back there is provided a blank integral therewith for the formation of the gasoline tank. This blank consists of a rectangular portion 99 with ears 100 on either side thereof spaced from the rear wall 97.

It will be seen upon examining Figures 24 and 26 that the blank is bent inwardly along the line 101 and again along the line 102 so that the tank to be formed is partially beneath the rear wall of the body. (See Fig. 29.) The portion beyond the flaps 100 which form the sides of the tank is bent down to form the rear of the tank. This is designated 99^a.

In Fig. 26 there will be seen the blank form for bending into final shape and weld-

ing. The outline of the doors is embossed at 103 and the window frames are made by the struck up portions 104. The flanges 105 are provided on the forward edges of 5 the side walls 89 and 88 for engaging with the body and supporting the wind shield structure. The lower edges of the side walls are curved inwardly in order that the flanges 107 which are in the vertical will lie flat 10 against the side walls 11 of the body to which the flanges 107 are welded. The rear edges 108 of the side walls are located beneath the flanges 96 of the rear wall of the body. Inwardly extending flanges 109 are 15 provided in the side walls adjacent the arch over the rear fenders in order to provide a broad surface for engaging with the tops 20 of the rear fenders which are thus overlapped by the bodies. The depending flanges 95 of the top overlap the free top 25 edges 110 of the side walls. As the rear portion of the top is narrower than the front portion these flanges 95 serve to hold the free, rearwardly extending portions of the body in a position which bows the side walls 30 of the body, giving a graceful appearance to the body and providing positive locking with the several parts to one another by having the flanges overlap.

30 In Fig. 30 will be seen a double bar bumper blank formed from a single piece of metal. The completed article is shown in Fig. 31. 111 designates the side bars, 35 112 the end bars and 113 are the ears for attaching the bumper to the frame member.

It will be understood that I do not desire to be confined to the details of my invention, but comprehend within it suitable modifications which may be found convenient in 40 adapting my invention to varying conditions.

Having thus fully described my invention, what I claim as new and desire to secure by Letters Patent, is:—

45 1. An automobile comprising three separable portions each cut and shaped from a single piece of metal, first, a body portion comprising a hood portion and sides, the sides terminating in rearwardly extending arms, second, a rear deck, seat, and floor portion with the rear deck extending over said 50 arms and the seat and floor extending between said sides, and third, a top portion interfitting with said other portions and extending 55 ing over the seat.

2. An automobile comprising three separable portions each cut and shaped from a single piece of metal, first, a body portion comprising a hood portion and sides, the sides terminating in rearwardly extending arms, second, a rear deck, seat, and floor portion with the rear deck extending over 60 said arms and the seat and floor extending between said sides, and third, a top por-

tion interfitting with said other portions 65 and extending over the seat, and one-piece running boards and fenders attached to said sides and arms.

3. An automobile comprising three separable portions each cut and shaped from 70 a single piece of metal, first, a body portion comprising a hood part and sides, the latter terminating in rearwardly extending arms, the hood portion having at its forward end a curved and slotted covering, 75 second, a rear deck, seat, and floor portion with the rear deck extending over said arms and the seat and front extending between said sides and, third, a top portion interfitting with said other portions and extending 80 over said seat.

4. An automobile having a one-piece body portion including a tapered hood portion with side portions terminating in arms extending back of the hood portion and a 85 one-piece rear deck, seat, and floor portion, said deck extending over said arms and the seat and floor portions adapted to extend down between the side portions and to be attached thereto.

5. An automobile having a one-piece body portion including a tapered hood portion with side portions terminating in arms extending back of the hood portion, and a 90 one-piece rear deck, seat, and floor part, said deck extending over said arms and the seat and floor portions adapted to extend down between the side portions and to be attached thereto and one-piece running 95 boards and fenders attached to said side portions and arms on either side thereof.

6. An automobile comprising a one-piece hood, and side frames, the hood portion being tapered and the side frames comprising substantially parallel sides extending to 105 the rear and front of the hood, the front extensions being provided with holes for the attachment of the front axle and the bumper and the rear extensions with cut-away portions to receive the rear wheels and driving mechanism.

7. An automobile hood and side frames formed from a single sheet of metal, the side frames extending back of and in front of the hood and having impressed therein body 110 panels, the side frames being substantially parallel to each other and the hood tapering from its rear to its forward end and having its top sloping downwardly from its rear to its forward end.

8. An automobile hood and side frames formed from a single sheet of metal, the side frames extending back of and in front of the hood and having impressed therein body 115 panels, the side frames being substantially parallel to each other and the hood tapering from its rear to its front end and having its top sloping downwardly to its forward end,

- and a one-piece end radiator curved outwardly and having overlapping flanges for engaging with the ends of the hood.
9. An automobile hood and side frames formed from a single sheet of metal, the side frames extending back of and in front of the hood and having impressed thereon body panels, the side frames being substantially parallel to each other and the hood tapering from its rear to its front end and having its top sloping downwardly to its forward end, a one-piece end radiator having overlapping flanges for engaging with the ends of the hood and a one-piece rear deck, seat, floor and dashboard, the rear deck engaging with the top of the side walls of the top and the seat, floor and dashboard extending down between the side walls.
10. An automobile hood and side frames formed from a single sheet of metal, the side frames extending back of and in front of the hood and having holes in their ends to receive the axles and driving parts, the side frames being substantially parallel to each other and the hood tapering from its rear to its front end and having a one-piece end radiator attached thereto, a one-piece rear deck, seat, floor and dashboard, the rear deck engaging with the tops of the side walls of the body and the seat, floor and dashboard extending down between the side walls, and a one-piece top extending over said seat and attached to said walls.
11. A one piece roadster top for a toy consisting of a top portion, side curtain members on either side thereof with ears to form stops and flanges to engage a body, and a rear wall portion with flanges for engaging with the side curtain members.
12. A one-piece running board and fender for an automobile consisting of a flat portion to form the running board and curved portions at either end thereof to form a front and rear fender, means on one side of said fenders for attaching the same to the body of the automobile, and marginal flanges on the other side, said attaching means and flanges being so arranged that when bent in one direction by the die, they form a left hand running board and fender and when bent in the opposite direction, they form a right hand running board and fender as described.
13. A windshield having one edge concaved, and the other edge convexed and the edge parallel, an I-shaped slot cut in the body thereof, one of the flaps adjacent the I-shaped slot being adapted to be moved to an angular position to form a wind-shield, and the other flap adjacent the I-shaped slot being adapted to be moved at an angle to form a dashboard ledge.
14. In combination, side frame members, slots therein for receiving bumper brackets, a bumper of one piece having laterally extending bumper brackets, the ends thereof projecting through the side frame members on the exterior thereof, and wheels carried by the side frame members and having rims to conceal the ends of the bumper brackets and to accommodate them.
- In testimony whereof I affix my signature.

CLARENCE E. FLORKEY.
